UNITED STATES PATENT OFFICE.

LÉON MAUBLANC AND NORBERT LALLIÉ, OF NANTES, FRANCE.

SHIP-PROPELLER.

1,074,513.

Specification of Letters Patent. Patented Sept. 30, 1913.

Application filed July 9, 1912. Serial No. 708,486.

To all whom it may concern:

Be it known that we, LÉON MAUBLANC and NORBERT LALLIÉ, citizens of the French Republic, and residents of Nantes, France, 5 have invented certain new and useful Improvements in Ship-Propellers, of which the following is a specification.

The present invention relates to a propeller screw the object of which is to so 10 arrange the blades that they may be spaced from the shaft from the front portion of the propeller to a supporting hub, whereby the blades will operate in still water.

Owing to the construction of the propeller, the entire surface of the blades are 15 efficiently utilized to avoid centrifugal effect in the mass of the expelled water, and loss of motive power. The propeller blades are so shaped that, while rotating, they generate 20 a cylinder and repel the whole corresponding cylindrical mass of water exclusively toward the rear at a uniform speed in the direction of the axis of the propeller shaft, so that each drop of water entering at one end 25 of the propeller slides all along the surface of a blade.

The view accompanying drawing illustrates a side elevation of the improved propeller.

30 At the rear end of the propeller shaft 1 is secured a hub 2. From two diametrically opposed portions of said hub two blades 3 and 4 symmetrically extend radially and normally with respect to said shaft and 35 thence forward in the direction of the motion (arrow 5) to the extent of half a pitch without contacting with the shaft 1. The inner edges of the blades 3 and 4, are spaced from the shaft 1, to provide a passage 6 for 40 the water said blades beginning at their inner edge with a slope of 30 degrees.

The rear inner portions 7 and 8 of the propeller blades 3 and 4 are as narrow as possible and the adapted slope is such that 45 it corresponds to the real speed of the repelled water, that is to say, to the speed transmitted to the water by the efficient portion of the blade, less the recoil.

From the foregoing it results that the im- 50 proved propeller is U shaped, the legs of the U being helically bent around the longitudi-

nal axis of the U in the direction of the ship's motion.

When the blades are in operation in water containing aquatic plants, the sharpened 55 edges act to cut the plants, and as no fastening arms or the like are provided between the front part of the blades and the shaft, the cut plants cannot become entangled with the blades. 60

An essential advantage of the improved propeller consists in that the blades, and especially their efficient working portions are operating in still water which is beyond the hub, that is to say the water which has not 65 been agitated or whirled either by a hub or by fastening arms.

Owing to the fact that the blades are secured at their rear ends, resistance of the water when the propeller is operating is 70 greatly reduced.

Having now fully described our said invention, what we claim and desire to secure by Letters Patent, is:

1. A propeller comprising a shaft, a hub 75 at the rear end of said shaft, two blades secured at two diametrically opposite points on said hub, said blades opposite the hub extending radially from said shaft, the blades extending forwardly in helical form around 80 said shaft and spaced therefrom to form a passage between said blades and the shaft from the front portion of the propeller to the hub.

2. A propeller comprising a shaft, a hub 85 at the rear end of the shaft, and blades secured to opposite sides of the hub and extending forwardly therefrom in helical form around the shaft, the inner edges of the blades from the hub being spaced from 90 the shaft to form a passage from the front portion of the propeller to the hub, the front edge of the blades being sharpened to form cutters.

In testimony whereof we have hereunto 95 set our hands in presence of two witnesses.

LÉON MAUBLANC.
NORBERT LALLIÉ.
